UNITED STATES PATENT OFFICE.

EDWARD F. MEAGHER, OF GLENDALE, OHIO.

SHADE-ROLLER FOR WINDOWS, PORCHES, OR THE LIKE.

SPECIFICATION forming part of Letters Patent No. 658,091, dated September 18, 1900.

Application filed January 31, 1900. Serial No. 3,431. (No model.)

To all whom it may concern:

Be it known that I, EDWARD F. MEAGHER, a citizen of the United States of America, and a resident of Glendale, in the county of Hamilton and State of Ohio, have invented certain new and useful Improvements in Shade-Rollers for Windows, Porches, or the Like, of which the following is a specification.

This invention relates to certain improvements in shades for windows, porches, and the like, and has for its object, in part, to provide a shade-roller of a simple and inexpensive nature and of a strong and durable construction, which shall not be liable to warp or spring out of line when in use, and in part to provide improved means for securing or attaching the shade to the roller, so as to obviate the liability of tearing the shade loose, as is commonly done when the shade is simply tacked to the roller in the ordinary way.

The invention consists in certain novel features of the construction, combination, and arrangement of the several parts of the improved shade, whereby certain important advantages are attained and the device is made simpler, cheaper, and otherwise better adapted and more convenient for use, all as will be hereinafter fully set forth.

The novel features of the invention will be carefully defined in the claim.

In the accompanying drawings, which serve to illustrate my invention, Figure 1 is a view showing the upper part of a shade embodying my invention, the central portion of the shade and roller being broken out for lack of space. Fig. 2 is an enlarged partial section taken longitudinally through the shade at one end of the roller. Fig. 3 is an enlarged end view of the roller, and Fig. 4 is an enlarged transverse section taken through the shade in the plane indicated by line *a a* in Fig. 1.

In the views, 1 indicates the body portion of the shade-roller, having at its ends fittings 2 and 3, each formed with a projecting pintle 4 to fit and turn in the bracket or fixture in a well-known way. The fittings 2 and 3 are formed of circular metal castings somewhat greater in diameter than the diameter of the body 1 of the shade-roller, so as to produce at the ends of the roller annular flanges or shoulders to prevent endwise movement of the shade when wound on the roller. The

fitting 2 is in the form of a metal disk, while the fitting 3 is, as herein shown, in the form of a grooved sheave or pulley to receive a curtain-cord (not shown) extending down in easy reach of the operator and adapted to be used for unwinding or winding up the shade on the roller.

The body of the shade-roller is formed of a length of metal tubing of suitable weight and diameter, having its ends closed, as clearly shown in Fig. 2, by plugs 5 of wood or the like, into the ends of which plugs are passed screws 6 for holding the fittings 2 and 3 in place upon the body. The fittings 2 and 3 are formed each with a circular recess or hollow 7 on its inner side of a diameter to snugly receive and house the end of the tubular body 1 of the shade-roller, so as to hold the plugs 5 securely in place therein as well as to afford a firm and solid mounting for the fittings.

8 indicates the shade, having one end 9 lapped over and secured to the body portion thereof by a transverse seam 10, so as to form at one end of the shade an open loop or pocket 11 to receive the shade-roller, which latter is preferably inserted in said pocket or loop before one or the other of the fittings 2 and 3 is applied to the body 1 of the roller, so as to permit said pocket to be made as narrow as possible. The pocket must, however, be of a size to fit the shade-roller only loosely, and in order to secure the shade to the roller to wind thereon I employ tacks 12 or the like, which are driven through the ends of the pocket 11 and also through the ends of the roller-body 1 and into the plugs 5 within the same, as clearly shown in Fig. 2. These tacks further serve to hold the plugs 5 securely in the ends of the body 1 of the roller.

To further secure the central portion of the shade 8 to the roller, I employ a cord or twine coiled spirally about the loop or pocket 11, as shown at 14 in Figs. 1 and 4, being passed through openings 13 in the shade, and after being drawn tight, knotted, or otherwise secured at its ends, as shown at 15, so as to securely bind the loop or pocket 11 upon the body of the roller between the tacks 12 at the ends thereof, and thus to secure the shade to the roller in such a manner that it will be compelled to wind upon the roller when the latter is turned.

The improved shade constructed as above described is extremely simple, strong, and durable, since the metal body 1 of the roller is not liable to warp or bend when in use, as 5 is commonly the difficulty in shades having wooden rollers, and also the recessed fittings 2 and 3 have a more secure bearing on the ends of said metal body than is possible in a wooden roller, and where the tubular body 10 portion is formed up from a sheet of tin or the like, as is commonly done in making metal tubing, these recessed fittings when secured over the ends of the said body portion serve to prevent the same from spreading at 15 the joint, whereby the plugs at the ends of the roller would be loosened. The shade itself is also not liable to be torn or pulled loose from the roller, as is the case when the shade is merely tacked to a wooden roller, 20 and the construction is such as to enable the shade to be easily and quickly applied to the roller.

It will also be obvious from the above description that the improved shade is not only 25 adapted for use at windows, but by reason of its strong and durable nature it is especially well adapted for use on porches and in other

exposed places where shades having wooden rollers are not fitted for use. Moreover, the device is capable of some modification without material departure from the principles and spirit of the invention, and for this reason I do not wish to be understood as limiting myself to the precise form and arrangement of the several parts herein shown. 30

Having thus described my invention, I claim—

In a shade for windows, porches and the like, the combination of a roller having a tubular metal body portion, a shade having one 40 end lapped over and sewed to the body of the shade to form an open loop or pocket to receive the roller, and a cord passed spirally around outside of the loop or pocket when in place on the roller and passed through openings in the shade and having its ends secured to bind the shade on the roller, substantially as set forth. 45

Signed by me at Cincinnati, Ohio, this 30th day of January, 1900.

EDWARD F. MEAGHER.
